ATTORNEY

UNITED STATES PATENT OFFICE.

ANGELO L. SORESI, OF NEW YORK, N. Y.

APPARATUS FOR SURGICAL USES.

Application filed May 17, 1924. Serial No. 713,878.

To all whom it may concern:

Be it known that I, ANGELO L. SORESI, a citizen of the United States, and resident of New York, county of New York, 5 and State of New York, have invented certain new and useful Improvements in Apparatus for Surgical Uses, of which the following is a specification.

This invention relates to an apparatus 10 for surgical uses, and more particularly has for its object to provide an improved device of simple construction, one which may be readily sterilized and one which may be subjected to continuous operation during 15 its operation.

More particularly it embodies means which are interchangeable, and also means for holding the balls which act as valves under restricted movement control, which 20 balls act also under the action of gravity, the apparatus when being used being so placed as to invoke the action of gravity in its operation.

The invention will be more fully described, hereinafter shown in the accompanying drawings and finally pointed out in the claims.

In the accompanying drawings,

Figure 1 is a perspective view of my improved apparatus.

Figure 2 is a central vertical section of a part of the same.

Figure 3 is a section taken on line 3—3 of Fig. 2, and

Figure 4 is a section taken on line 4—4 of Fig. 2.

Figure 5 is a section taken on line 5—5 of Fig. 2.

Similar characters of reference indicate 40 corresponding parts throughout the various views.

Referring to the drawings and more particularly to Figure 1, my improved apparatus comprises a frame or standard 10, consisting of a vertical member 11, having three lateral brackets 12, 13 and 14, either secured thereto or made integral therewith. The two lower brackets 13 and 14 serve in part the function of attaching the apparatus 45 to a table or the like and for this purpose a clamp screw 15 is provided. The bracket 13 serves the further purpose of supporting the standard 16 on which the instrument rests. The bracket 12 supports the syringe 50 18 of the instrument. Suitable thumb screw 19 serves to enable the portion 20 of the

instrument to be raised or lowered so as to adapt it to the syringe.

The syringe is of well-known construction, consisting essentially of a tubular or 60 cylindrical member 21 closed at 22 and 23, the closure 23, having an opening communicating with the taper joint connection 24. A piston 25 operated by the handle 26, passing through an opening in the closure 22 65 acts as a pump.

The instrument itself consists of a casing 30 which is bored out symmetrically at the upper and lower portion thereof in substantially conical shape. Into these conical cavities there are inserted members 31 and 32, which are interchangeable. The member 31 has a shoulder 33 and a conduit channel 34, having an enlarged portion 35 and an outlet portion 36. Over the shoulder 33 a screw cap 37 is provided, which engages the corresponding screw threads of the casing 30. The member 32 is similarly arranged, its extension 20 seating in the standard 16 and being held by the 70 thumb screw 19. The casing 30 is further provided with a center bore acting as a conduit, indicated by 39, and this has a lateral channel 40 communicating therewith, which is of tapering shape and forms 75 the interior of the member 24 attached to the pump cylinder hereinbefore referred to.

The casing is further provided with a conical seat 41 for the upper ball valve 42 and at the other end of the conduit 39 80 the casing is provided with a cavity 43 which permits the lower ball 44 to move therein. It will be noted that the seat 41 and the cavity 43 are quite close to each other. In other words, the channel or conduit 39 is of relatively short length. It 85 will also be noted that the cavities permit

a limited freedom of movement to the balls, which however, are restricted in their movement. Gravity acts to cause the balls to descend to their seats. No springs are used. 90

To the end 36 of conduit 34 a tube 34^a to which a needle is applied may be readily attached and when used this tube and needle serve to convey the blood or other fluid to the recipient. The other, or inlet member 36^a may have a tube 36^b attached thereto, also provided with a needle, and this serves to receive the blood from the donor, or the fluid which it is desired 100 to inject into the body. In the latter case, a needle is dispensed with, and the tube is 105 110

inserted into a container holding the fluid. If the apparatus is used for drawing pus or the like from a body, then a needle is applied to the tube attached to the inlet end 36^a and the needle on the tube 34^a is dispensed with.

The operation of my improved device for blood transfusion is as follows:—

After the device and tubes and needles have been thoroughly sterilized, the needle of the tube 36^b engaged with the inlet 36^a is inserted into the donor and then the needle attached to the tube 34^a, is inserted into the recipient. The pump is then actuated. The actuation of the pump by its suction, serves to raise the ball 44 from its seat against the action of gravity and thereby the blood is drawn through the conduit and into the cylinder of the syringe or pump, the other ball 42 being drawn tightly by the suction created against its seat 41, being aided by the action of gravity. The counter movement of the piston of the syringe or pump then presses the ball 44 against its seat being aided by gravity, raises the ball 42 from its seat against the action of gravity, and forces, by pressure, the blood through the conduit 34, out of the outlet 36 and through the needle into the recipient.

It will be noted that the casing 30 is arranged in vertical position, as a result of which the balls 44 and 42 are under the action of gravity at all times and their movement in the vertical direction against the action of gravity is overcome by the suction of the pump in the one case; and by the pressure of it in the other case. It is essential to place the apparatus in vertical position, as otherwise it will not work. This is very important since the action of the device takes into consideration the action of gravity. The operation described is repeated by the action of the piston in the pump or syringe and as a result thereof a continuous transfusion of the blood takes place from the donor to the recipient. The action is immediate and rapid and the blood so transfused is not subjected to injection, but on the contrary the instruments and parts thereof act in the nature of a continuous communication between donor and recipient.

Preferably in such cases where fluid is injected, the needle orifice of the recipient is smaller than that of the donor, whereby in the tube at the recipient end, an accumulated pressure results, which aids in the injection.

The action of the device is very positive and quickly responsive to the movement of the syringe.

After the blood has been transfused, the needles are extracted, the instrument is cleaned, and it is then ready for another use.

The device has the further advantage that it may be readily cleaned, in that the caps 37 and 37^a are removed and the members 31 and 32, as also the casing, are then subjected to an intense sterilization. After this, they are again assembled and the device is ready for further use.

It will be particularly noted that the action of the balls is under the force of gravity that the balls are in restricted cavities which limit the movement of the balls.

I have described the use and the operation of my improved apparatus in connection with blood transfusion. But the apparatus may also be used for hypodermoclysis, thoracentesis, paracentesis, infiltration anaesthesia, intravenous injection, etc. It is of course, clear that in certain of these uses, as for instance in thoracentesis and paracentesis the needle is applied to the inlet tube which needle is then inserted in the locality desired to be treated, and the outlet tube then acts only as a discharge tube of the matter extracted from the body. In hypodermoclysis, infiltration and intravenous injections, the inlet tube has its needle removed and is inserted into a container holding the fluid to be utilized and the outlet tube has applied thereto its needle which is inserted into the body. As before stated, in such cases where fluid is injected into the human body it is advantageous to have the orifice of the inlet opening or the orifice of the inlet tube larger than the orifice of the outlet tube, or in other words, larger than the orifice of the needle. In view thereof an accumulated pressure is obtained so that with each action of the pump the accumulated pressure assists in injecting the fluid into the human body, against the pressures therein present. It has been found, for instance in the use of syringes or pumps heretofore employed, that a considerable effort was necessary to force the fluid into the human body against the pressures therein contained and the operator soon became fatigued by exerting the force necessary. In the device hereinbefore described and shown in the drawings the pump or syringe is relatively small and comparatively little effort on the part of the operator is necessary, the reason for this being the simplicity of the operation of the parts, particularly in that the balls are restricted in their movements and in certain positions are aided by the acts of gravity and also by the accumulated pressure reservoir within the conduits, hereinbefore described. In view thereof, my device can be readily manufactured, is of comparatively small size, and hence can be made at very little expense.

I have described one embodiment of my invention but do not wish to be limited in the details thereof since changes may be made without departing from the spirit of the invention, as defined in the appended claims.

I claim as new:

1. An apparatus for surgical uses comprising, a casing having a longitudinal bore therethrough and a transverse bore communicating with said longitudinal bore between its ends, a pump or syringe adapted to be connected with said transverse bore, end members adapted to removably engage the ends of said casing, said end members having bores through them communicating with the longitudinal bore in said casing and providing in conjunction therewith valve cavities, ball valves in said valve cavities for preventing the flow of fluid through said end members and casing in one direction, and inlet and outlet conduits communicating with the bores in the end members.
2. An apparatus for surgical uses comprising, a bracket clamp, an upright supporting member adapted to be connected therewith, a casing member having a longitudinal bore therein arranged vertically on the upper end of the said supporting member, inlet and outlet conduits communicating with the upper and lower ends of said bore, said bore having a pair of spaced enlarged cavities providing valve chambers and having
3. An apparatus for surgical uses, comprising a casing having two conical cavities, insert members for said cavities, each having a center conduit and a valve seat, valve seats in the casing, a conduit in said casing connecting said valve seats, a conduit at right angles thereto, a pump or syringe adapted to be connected therewith, an inlet for one of said insert members, an outlet for the other of said insert members, and means for holding the insert members tightly in the cavities of the casing.

In testimony that I claim the foregoing as my invention, and have signed my name hereto.

ANGELO L. SORESI.
